UNITED STATES PATENT OFFICE.

ROBERT McALPINE, OF ST. MARYS, ONTARIO, CANADA.

TELEPHONE-MOUTHPIECE SANITARY CAP.

Application filed September 30, 1927. Serial No. 223,055.

This invention relates to a telephone mouthpiece sanitary cap, as described in the present specification and illustrated in the accompanying drawings which form part of 5 the same.

The invention consists essentially of the novel features pointed out broadly and specifically in the claims for novelty following a description containing an explanation in 10 detail of an acceptable form of the invention.

The objects of the invention are to provide sanitary caps of simple construction and that can be easily and quickly fastened 15 upon and removed from a telephone mouthpiece; to produce such a cap so cheaply as to be within the reach of the whole public, therefore encouraging the use of such sanitary and disease-preventing devices; and 20 generally, to improve upon such known devices.

In the drawings, Figure 1 is a top plan view of a device made according to this invention.

25 Figure 2 is a section on line 2—2 in Figure 1.

Figure 3 is an elevation of Figure 1.

Figure 4 is a top plan view of another 30 form of the invention wherein other means are used for fastening the device upon the mouthpiece.

Figure 5 is an elevation of Figure 4.

Figure 6 is a bottom plan view of Figure 4.

35 Figure 7 is a section on line 7—7 in Figure 4, illustrating the working of the fastening means by giving the representation of a hand in the act of fastening the device upon the mouthpiece.

40 Figure 8 illustrates the device as applied to the mouthpiece and ready for use.

Referring to the drawings, 10 is a circular disc of relatively stiff paper or other suitable pulp substance, having a centrally-located opening 15 and formed into a substantially cup-like shape by turning the edge to provide a flange 11; the flange is provided with a number of spaced slits 12 cut thereinto so as to present a serrated or 45 expandible flange, thus permitting any portion of the flange to be expanded or bent out of its normal position or shape without affecting the remaining portion of said flange. The flange is turned in sufficiently to leave 50 the inner diameter D smaller than the diameter D1 of the telephone mouthpiece so that

the flange, by embracing the outer rim portion of the mouthpiece, serves the means of retaining the device in operative position upon the mouthpiece.

14 is a second disc of relatively soft porous paper, preferably tissue paper, of a diameter larger than the inside diameter D3 of the disc 10, so that by applying the disc 14 upon the inside face of the disc 10, as 60 shown, the edge of the disc will curl or bend, forming a flange 12A engaging the flange 11. The inside disc 14 is thus retained in position by friction securely enough to make the device complete a practical one for the purposes intended thereof.

In Figures 4 to 7, a slight modification in the form of the invention is disclosed. The flange 11A is bent substantially at right angles and is extended at a number of points 70 to provide lugs 20. The lugs are turned in as shown and are made long enough to engage the outer rim of the mouthpiece when the device is pushed into position, as best illustrated in Figure 7. As also suggested by Figures 7 and 8, the relative length of the flange 11A and the lugs 20 is made such that once the device is upon the mouthpiece (as shown in Figure 8) the lugs are free to spring back into their normal position and 75 therefore form the means of holding the device in operative position upon the mouthpiece. The lugs 20 assist in retaining the disc 14 on the member 10 should said disc move from its intended assembled position 80 relative to said member.

The tissue paper 14 should vibrate sufficiently to properly transmit sounds, and it is to be noted that by leaving the disc free except at its edges, the vibrating properties 85 of this disc are increased. If it is desired, the disc 14 may be secured to the member 11 by glueing one to the other at a few separated points along the flange 12A.

Operation: In applying the device made 90 to the form shown in Figures 1 to 3, it is grasped preferably between the thumb and the first finger and held at an angle to the vertical. The device is then first made to engage the upper or lower portion of the 95 mouthpiece rim so as to expand locally one part of the flange 11, and the device then swung to a vertical position to cause the remaining portion of the flange 11 to engage the remaining portion of the mouthpiece 100 rim. In applying the device made to the form shown in Figures 4 to 6, the device is 110

grasped preferably between the thumb and first finger and pushed onto the mouthpiece, as clearly suggested in Figure 7.

After the telephone conversation has been completed, the device is thrown away, since its relatively small cost easily permits of so doing.

What I claim is:

1. In a telephone mouthpiece sanitary cap, a circular perforated disc having a flange therearound, and a second disc of relatively soft paper laid upon said first-mentioned disc and made to a diameter larger than that of said disc and having the edge

turned to frictionally engage the flange in 15 said first-mentioned disc.

2. A telephone mouthpiece sanitary cap comprising a cup-shaped member of relatively stiff paper having an opening therethrough and a flange adapted to embrace the 20 outer rim portion of said mouthpiece and retain said member thereupon, and a disc of tissue paper laid upon said member and bent along the edge to form a flange engaging said first-mentioned flange. 25

Signed at the city of Toronto, this 1st day of September, 1927.

ROBERT McALPINE.
